UNITED STATES PATENT OFFICE.

WILLIAM G. HAGMAIER, OF WEST ALLIS, WISCONSIN, ASSIGNOR TO ALLIS-CHALMERS MANUFACTURING COMPANY, OF MILWAUKEE, WISCONSIN, A CORPORATION OF DELAWARE.

TIMBER-MANIPULATING MECHANISM.

Application filed March 18, 1922. Serial No. 544,726.

To all whom it may concern:

Be it known that WILLIAM G. HAGMAIER, a citizen of the United States, residing at West Allis, in the county of Milwaukee and State of Wisconsin, has invented a certain new and useful Improvement in Timber-Manipulating Mechanism, of which the following is a specification.

This invention relates in general to improvements in the construction and operation of sawmill machinery, and relates more specifically to improved mechanism for loading and adjusting timber in sawmills.

An object of the invention is to provide simple and efficient timber loading, unloading and adjusting mechanism. Another object of the invention is to provide improved mechanism which is especially adapted for loading and adjusting timber upon sawmill carriages. A further object of the invention is to provide a combined nigger bar and push arm structure for sawmills, which is simple and compact in construction and efficient in operation. Still another object of the invention is to provide an improved timber adjusting arm which is swingable about an axis and which is readily removable from its support. Another object of the invention is to provide a stop plate for nigger bars, which may be located near the effective part of the bar and above the push arm rock shaft which is located in proximity to the nigger bar. These and other objects and advantages of the present invention will be apparent from the following description.

A clear conception of an embodiment of the invention and of the operation of mechanism constructed in accordance therewith, may be had by referring to the drawing accompanying and forming a part of this specification, in which like reference characters designate the same or similar parts in the various views.

Fig. 1 is a top view of a combined nigger bar and push arm mechanism for sawmills.

Fig. 2 is a part sectional side elevation of a combined nigger bar and push arm mechanism for sawmills, showing a sawmill carriage and a piece of timber in operative relation thereto.

Fig. 3 is an enlarged fragmentary side elevation of a combined nigger bar and push arm mechanism for sawmills.

Fig. 4 is an enlarged fragmentary side elevation of an improved push arm.

Fig. 5 is an enlarged central vertical section through a coupling for connecting the push arm to the rock shaft.

The timber adjusting mechanism illustrated in Figs. 1, 2 and 3, comprises in general, a horizontal two-piece rock shaft 2, 3 supported in bearings associated with the forward end of an A frame 8, a bifurcated push arm 4 attached to and swingable by the rock shaft 2, 3, an operating cylinder 6 and a reciprocable piston 7 oscillatably supported in bearings 15 associated with the rear end of the A frame 8 and cooperating with the upper swinging extremity of the push arm 4, an upright nigger bar 5 movable laterally within the bifurcation of the push arm 4 and in proximity to a piece of timber 19 resting upon the carriage 17, and actuating mechanism or cylinders 22 for manipulating the nigger bar 5.

The horizontal rock shaft comprises two aligned shaft sections 2, 3, the adjacent ends of which extend into the bifurcation of the push arm 4 and are spaced axially apart. A coupling element or collar 10 shown in detail in Fig. 5, is secured to each of the shaft sections 2, 3 by means of a key engaging key-ways 26, the collars 10 being formed in one piece and snugly fitting the shaft sections 2, 3. The prongs of the push arm 4 are formed as illustrated in Fig. 4 with recesses 24 whereby the push arm prongs are adapted to be slid laterally of and into engagement with the shaft sections 2, 3 directly adjacent to and between the collars 10. The push arm prongs are rigidly attached to the adjacent collars 10, by means of bolts passing through aligned openings 25 in the collars 10 and the push arm 4. The push arm actuating cylinder 6 is provided with laterally projecting trunnions which are supported in the bearing 15 associated with the rear portion of the A frame 8. Actuating fluid for reciprocating the piston 7 within the cylinder 6 may be admitted to and exhausted from the cylinder through piping 16, the admission and exhaust of this fluid being controlled by means of a valve mechanism 20 and valve actuating connections 21.

The nigger bar 5 is vertically and laterally reciprocable by means of the actuating mechanism 22 in a well known manner. The bar 5 is swingable within the bifurcation of the arm 4 and across the axis of the 110

rock shaft sections 2, 3. A stop plate 9 is located above the axis of the rock shaft and closely adjacent to the carriage 17, is provided at its forward face with a front 5 stop plate 14, and at its rear face with a rear stop plate 13, these stop plates being interconnected by means of bolts 23, a reaction plate 12, and springs 11, in such a manner that the lateral movement of the 10 nigger bar 5 is cushioned in both directions. The rock shaft bearing caps 27 are located in recesses formed in the stop plates 9 and 15 coact with the extreme inner ends of the shaft sections 2, 3. The carriage 17 is movable past the push arm 4 and nigger bar 5 in a well known manner, and is adapted to support a piece of timber such as the 20 log 19 which is normally held in position upon the carriage by means of gripping mechanism 18.

The floor of the carriage 17 is located in approximately the same horizontal plane as that of the stationary log deck or timber supporting means from which the logs are 25 delivered to the carriage. The axis of the rock shaft 3 is preferably located some distance below the log supporting surface of the deck and as near to the carriage 17 as possible, in order to permit the oscillating 30 push arm 4 to effectively urge the logs resting upon the deck along the upper surface thereof.

During normal operation of the device, the 35 push arm 4 may be oscillated about the rock shaft 2, 3 to convey logs from a suitable skidway onto the carriage 17 by admitting fluid under pressure to the actuating cylinder 6. After a piece of timber 19 has been 40 properly positioned upon the carriage 17, the push arm 4 is swung back to the position illustrated in Figs. 1 and 2 by admitting fluid under pressure to the cylinder 6. If 45 it is desired to adjust the timber 19 upon the carriage 17, such adjustment may be effected, either by means of the push arm 4 and other mechanism carried by the rock shaft 2, 3, or by means of the nigger bar 5 which may 50 be manipulated to cause the teeth thereof to engage the periphery of the timber 19 and to make the desired adjustment. During such manipulation of the nigger bar 5, the bar 55 may be swung laterally, that is fore and aft, within the bifurcation of the push arm 4, the forward and rearward movement of the bar 5 being cushioned by the springs 11 mounted 60 upon the stop plate 9. When the timber 19 has been properly adjusted on the carriage, the nigger bar 5 and the push arm 4, may be positioned as indicated in the drawings, thereby permitting free movement of 65 the carriage 17 past the timber adjusting mechanism.

It will be noted that by locating the nigger bar stop plate 9 and the front and rear 65 stop plates 14, 13 above the axis of the rock

shaft 2, 3, movement of the bar 5 is restrained in close proximity to the effective portion of the bar 5 thus producing maximum stability of the bar 5 while in operation. The stop plate 9 also protects the 70 bearing caps 27 of the rock shaft sections 2, 3, which caps are located directly adjacent to the prongs and within the bifurcation of the push arm 4. The push arm 4 may be conveniently and rapidly removed from the 75 rock shaft sections 2, 3 by removing the clamping bolts from the holes 25 and withdrawing the arm 4 laterally away from the rock shaft sections. The entire structure is compact and rugged thus adapting the same 80 to the service required of such apparatus.

It should be understood that it is not desired to limit the present invention to the exact details of construction and of operation herein shown and described for various 85 modifications within the scope of the claims may occur to persons skilled in the art.

It is claimed and desired to secure by Letters Patent:

1. In combination, means providing a 90 timber support, a timber adjusting arm swingable about a pivot located below said support, a timber adjusting bar movable adjacent to said arm and above said support, and means for limiting the movement of 95 said bar, said movement limiting means being located in proximity to said support and above the pivot of said arm.

2. In combination, means providing a timber support, a bifurcated timber adjusting 100 arm swingable about a pivot located below said support, a timber adjusting bar movable within the bifurcation of said arm and above said support, and means for limiting the movement of said bar, said movement limiting 105 means being located in proximity to said support and above the pivot of said arm.

3. In combination, means providing a timber support, a timber adjusting arm swingable upwardly about a horizontal pivot located 110 below said support, an upright timber adjusting bar movable laterally adjacent to said arm and above said support, and means for limiting the lateral movement of said bar, said movement limiting means being 115 located above the pivot of said arm and below said support.

4. In combination, means providing a timber support, a bifurcated timber adjusting arm swingable about a horizontal pivot located 120 below said support, an upright timber adjusting bar movable laterally within the bifurcation of said arm and above said support, and means for limiting the lateral movement of said bar, said movement limiting 125 means being located above the pivot of said arm and below said support.

5. In combination, means providing a timber support, a timber adjusting arm, a rock shaft located below said support and form- 130

- ing a horizontal pivot about which said arm is swingable, a timber adjusting bar movable in proximity to said rock shaft and above said support, and means for limiting the movement of said bar, said movement limiting means being located above said rock shaft and below said support. 40
6. In combination, means providing a timber support, a bifurcated timber adjusting arm, a rock shaft interrupted at the bifurcation of said bar and forming a pivot located below said support about which said arm is swingable, a timber adjusting bar movable in the bifurcation of said arm and across the axis of said shaft, and means for limiting the movement of said bar, said movement limiting means being located in proximity to said support and above the pivot of said arm. 45
7. In combination, means providing a timber support, a bifurcated push arm, a rock shaft interrupted at the bifurcation of said arm and forming a horizontal pivot located below said support about which said arm is swingable, an upright nigger bar movable within the bifurcation of said arm and across the axis of said shaft, and a stop plate for limiting the movement of said bar, said stop plate being located above said rock shaft and below said support. 50
8. In combination, means providing a timber support, a bifurcated timber adjusting arm, a pivot shaft for said arm interrupted at the bifurcation thereof, said shaft being located below said support and having portions extending into said arm bifurcation, a timber adjusting bar movable between said shaft portions, and a stop plate for said bar 55
- located directly above said shaft portions and below said support. 60
9. In combination, a bifurcated timber adjusting arm, a rock shaft forming a pivot about which said arm is swingable, a timber adjusting bar located between the bifurcations of said arm, and means for effecting removal of said arm from said rock shaft by moving said arm transversely of the axis of said shaft and laterally away from said bar. 65
10. In combination, push arm, a rock shaft forming a pivot for said arm, a bifurcated member secured to said rock shaft and to said arm, a timber adjusting bar located between the bifurcations of said arm, said arm being laterally removable from said shaft and away from said bar upon removal of the securing means between said arm and said member. 70
11. In combination, a rock shaft, an arm having a forked end engaging said shaft, a timber adjusting bar located between the prongs of said arm, and means for securing said arm to said shaft, said arm being freely removable laterally of the shaft axis and of said bar upon release of said securing means. 75
12. In combination, a pair of aligned shafts having adjacent ends spaced apart, a collar embracing each of said shaft ends, a bar movable between said collars, and a bifurcated arm connecting said collars, said arm being laterally removable from said shaft and away from said bar when disconnected from said collars. 80

In testimony whereof, the signature of the inventor is affixed hereto.

WILLIAM G. HAGMAIER.
